J. S. NAKASHIAN

PROCESS FOR STRAIGHTENING RUGS

Filed Aug. 16, 1926

Patented Oct. 16, 1928.

1,688,088

UNITED STATES PATENT OFFICE.

JACOB S. NAKASHIAN, OF WATERTOWN, MASSACHUSETTS.

PROCESS FOR STRAIGHTENING RUGS.

Application filed August 16, 1926. Serial No. 129,636.

This invention relates to an improved process for straightening or correcting inequalities in the shape of floor rugs, particularly oriental rugs. Many oriental rugs are 5 missshapen in several ways, some of these rugs are shorter on one edge than on the edge which is oppositely disposed thereto; sometimes the difference in length amounting to several inches; they are also curled at the 10 edges, up or down, more or less, so that they will not lie flat upon the floor.

Efforts have been made to overcome these deficiencies and to correct the shape of the rugs so that they will lie flat and have their 15 oppositely disposed edges of the same length. One process for attempting to arrive at this result has been to mark the correct shape and size of the rug on a floor or board and then, by means of hand pliers, to stretch the 20 rug until it assumes the dimensions of the shape thus marked out, the edge of the rug being tacked to the floor or board, and then thoroughly wetting the rug with water and sometimes with starch.

25 The result attained by this latter process is merely to straighten the fibers of wool in the rug, and when the rug is again exposed to any dampness, the threads return to their original shape and the rug again becomes 30 missshapen. This old process also takes a long time for the rug to dry when it is lying in contact with and tacked down to the floor.

The object of this invention is to overcome 35 the difficulties hereinbefore encountered and to straighten the rug so that it will remain permanently straight and lie flat upon the floor.

The invention therefore consists in the process of straightening a rug hereinafter 40 described and particularly pointed out in the claim.

The preferred form of apparatus for straightening the rugs by my improved process is illustrated in the accompanying drawings in which—

45 Figure 1 is a plan view of the apparatus, a rug after having been straightened being shown in dotted lines in connection therewith.

50 Fig. 2 is a front elevation of the said apparatus partly broken away and shown in section.

Fig. 3 is a plan view of a rug, one edge of 55 which is shorter than the other and illustrates one form of missshapen rug which can

be straightened by my improved process utilizing the apparatus disclosed in Figs. 1 and 2.

Like numerals refer to like parts in the several views of the drawings.

In the drawings, 5 and 6 are longitudinal members of the apparatus and 7 and 8 are cross members thereof. The cross member 7 is provided with a groove 9 extending longitudinally thereof, in which is positioned a bar 10 which clamps one end of a rug 11 in the groove 9, pressure being applied to the bar to perform the clamping operation by a usual form of C clamp 12 consisting of a frame 13 and screw 14 having a swivel 15 which bears upon the clamp bar 10, the end 16 of the frame bearing against the under side of the cross member 7.

In the drawings there are two of the clamp members shown in connection with the cross member 7, but it is evident that as many of the C clamps may be utilized as may be desirable.

Brackets 17 are fastened to the underside 80 of the cross member 7, adjacent its opposite ends and are supported by and have screw-threaded engagement with adjusting screws 18 which are rotatably mounted at their opposite ends in brackets 19, two of which are fastened to each of the longitudinal members 5 and 6. Each screw 18 is provided with a handle 20, by which it may be rotated and thus move the cross member 7 toward or away from the cross member 8 in order to stretch the rug in a manner hereinafter more 85 particularly described.

The cross member 8 has pins 21 and 22 adjacent its opposite ends and projecting downwardly therefrom into holes 23 and 24 in the longitudinal members 5 and 6, which 90 are provided with graduations 23' and 24', whereby the cross member 8 can be approximately positioned according to the length of the rug which is to be stretched. The cross member 8 is provided with a clamping bar 100 25, which is positioned in a groove 26 extending longitudinally of the cross member 8, which is adapted to clamp one end of the rug 11 in the groove 26 by means of the C clamps 27 which are of the same construction as the 105 C clamps 12.

The missshapen rug illustrated in Fig. 3 embodies a short side 28, an oppositely disposed longer side 29 and ends 30 and 31. The process whereby this rug may be 110

straightened is as follows:—The end 30 of the rug is clamped by the bar 25 and the C clamps 27 in the groove 26 preferably with the face side of the rug down as illustrated in Fig. 2. The other end 31 of the rug is then clamped to the cross member by the bar 10 and the C clamps 12. When placing the rug in the groove 9 of the cross member 7 preparatory to clamping the same to said cross member, the end 31 is brought around into substantial parallelism with the end 30, thus producing considerable slack in the rug, which is of greatest amount along the long side 29 of the rug. The end 31 having been clamped in the cross member 7 in approximately the position indicated by dotted lines, Fig. 3, relatively to the end 30, the first step in the process is to take up the slack of the rug in the line of direction of the short side 28. The rug is then dampened lengthwise thereof adjacent to the short side 28. The dampening of the rug is preferably performed by spraying the same with water, the rug being thus dampened but not saturated with water.

The next step in the process is to beat the dampened portion of the rug lightly with a suitable rod for the purpose of distributing the moisture more uniformly and to stretch the fabric, and again the rug is made taut by means of the screws 18 to take up the slack. The dampened portion of the rug is now preferably dried by ironing the same with a hot iron. After the rug is dried, the process of dampening, beating and taking up the slack and drying is repeated until the rug has been stretched, and the slack throughout the whole width of the rug has been taken up by means of the dampening, beating, and stretching, so that the whole rug will then be perfectly flat and equally taut, and the two sides 28 and 29 will be of approximately the same length, thus the rug will have become correctly shaped, and it is then kept in the frame until it is absolutely dry.

This drying process does not take long, as there has been a comparatively small amount of moisture applied to the rug, and it will be noted that the rug is suspended during all of the foregoing operations so as not to come in contact with the floor or bench upon which the apparatus is positioned.

It has been found by practical use that a rug shaped by this process will lie perfectly flat upon the floor and will retain its correct shape indefinitely. This result is attained by the process hereinbefore described, in which the yarns of which the rug is com-

posed are dampened and beaten and stretched until they assume new positions and lengths relatively to each other and to the yarns interwoven therewith and crossing the same. In this manner a permanent change is imparted to the rug and the warp and weft of the rug assume new and permanent relations to each other.

While I have described my improved process for straightening or correcting the shape of rugs, particularly in relation to a rug, one side of which is longer than the side oppositely disposed thereto, the process is equally well adapted to correct other inequalities in rugs, such for example, as the curling of the edges, or the distortions of different portions of the rug, whereby a plait or fold, or slack portion appears therein. The process hereinbefore described is applicable to the correcting of all such inequalities and malformations, the rug being alternately dampened, beaten, stretched and dried until such defects have been eliminated.

I have represented the rug in dotted lines extending just outside of the longitudinal members 5 and 6; that is a matter of detail. Generally the frame would be adjusted so that the edge of the rug would come slightly inside of the longitudinal members 5 and 6.

It is apparent that the apparatus may be used to stretch and correct irregularities in a rug by applying it crosswise of the rug as well as lengthwise,—that is to say by clamping the sides instead of the ends of the rug in the cross members 7 and 8, and proceeding with the same steps of dampening, beating and stretching above described. If desired while stretching lengthwise, at the same time the rug may be held taut transversely by clamping or otherwise securing the sides to the longitudinal members 5 and 6.

I claim:

The process of straightening a rug having oppositely disposed edges of different lengths, which consists in suspending the rug and taking up the slack thereof in the direction of the shorter edge, then dampening the rug along the portion adjacent the shorter of said edges, then lightly beating the dampened portion of the rug to stretch said portion longitudinally of said edge, then taking up the slack of said dampened portion, then causing the rug to dry while suspended under tension.

In testimony whereof I have hereunto set my hand, this 27th day of July, 1926.

JACOB S. NAKASHIAN.
